UNITED STATES PATENT OFFICE

OTTO F. STOCK, OF COLUMBUS, OHIO, ASSIGNOR TO THE JULIAN & KOKENGE CO., OF COLUMBUS, OHIO, A CORPORATION OF OHIO

DESIGN FOR A SHOE

Application filed April 25, 1933. Serial No. 47,893. Term of patent 3½ years.

To all whom it may concern:

Be it known that I, Otto F. Stock, a citizen of the United States, residing at Columbus, in the county of Franklin and State of Ohio, have invented a new, original, and ornamental Design for a Shoe, of which the following is a specification, reference being had to the accompanying drawing, forming a part thereof.

The figure is a perspective of a shoe showing my new design.

I claim:

The ornamental design for a shoe as shown.

OTTO F. STOCK.
